UNITED STATES PATENT OFFICE.

HUGO MELOCCO, OF BUDAPEST, AUSTRIA-HUNGARY.

WATCH.

1,153,559.

Specification of Letters Patent. Patented Sept. 14, 1915.

Application filed March 2, 1911. Serial No. 611,854.

To all whom it may concern:

Be it known that I, HUGO MELOCCO, manufacturer, of Budapest, Austria-Hungary, have invented certain new and useful Improvements in Watches, of which the following is a specification.

The present invention relates to a watch provided with a time-beating mechanism, which is capable of being connected in such a way with the driving mechanism of the watch, that it is actuated by the latter without interfering with the ordinary working of the watch. The time-beating mechanism in this way beats a certain regular time which may be determined in advance, so that the watch may be used not only for measuring the time, but also for controlling and keeping time of all movements which have to be executed in regular intervals. The time-beating mechanism may be constructed in such manner, that it can be used for different times.

The watch forming the subject matter of the invention can be practically employed for many purposes.

The accompanying drawing shows the watch in the form especially adapted to be used for the control of military marches.

Figure 1. is a view of the inner mechanism of the watch on a larger scale. In this figure only such parts of the mechanism are shown, which are necessary for demonstrating the invention. Fig. 2. is a view of the dial plate, and Fig. 3 is a side view of the change speed mechanism detached, as viewed in the direction of the arrows on line $\alpha-\alpha$ Fig. 1.

The watch mechanism is provided with the well known spring-driven wheel —1— (Fig. 1.), the minute hand wheel —2—, the intermediate wheel —3—, the second hand wheel —4— and the balance —5—. These wheels work in the usual way, that is to say the wheel —1— acts upon the toothed wheel —6— on the axle of the wheel —2—, the wheel —2— acts upon the toothed wheel —7— on the axle of the wheel —3— and the wheel —3— acts upon the toothed wheel —8— on the axle of the wheel —4—.

According to the invention, the rearplate of the watch-case, upon which the axles of the watch mechanism bear, supports besides the known elements of the watch mechanism, also the elements of the time-beating mechanism. On the axle —9— above the wheel —2—, as many arms —10— are turnably ar-

ranged one above the other, as different times shall be beaten by the time-beating mechanism. In the present case, six of such arms 10 as seen in Fig. 3 are employed. In 60 the present case the time-beating mechanism is constructed for six different times according to the most usual number of steps of military marches, that is to say for 90, 95, 100, 105, 110 and 115 steps in the minute. 65 On the axle —9— in this way altogether six arms —10— are arranged, each of which on its under side bears a toothed wheel —11—. Under the supported end of each arm —10— one toothed wheel —12— for each arm 10 70 is turnably arranged on the axle —9—. Each of these wheels —12— lies in the same plane as the appertaining wheel —11— and remains in constant connection with same, so that by turning one of the wheels —11— 75 the corresponding wheel —12— also will be turned.

On the axle —8— of the second hand wheel —4— six toothed wheels —13— are mounted above one another, each of which 80 has a different number of teeth and lies in the plane of one of the wheels —11—, so that by turning one of the arms —10— around the axle —9— toward the wheel —13—, the toothed wheel —11— of the 85 turned arm will gear with the corresponding wheel —13— and will be turned by means of that wheel and the aid of the second hand wheel —4—. The number of teeth of the wheels —13— is determined according to the above mentioned different times, preferably with regard to the circumstance, that in military marches always 90 every second step, especially that of the left leg is counted, so that the time-beating 95 mechanism does not need to beat but every second time, that is to say only the half of all times.

In order that always that wheel —13— 100 may come into connection with the corresponding wheel —11—, which corresponds to the time to be beaten, the following well known gearing device is arranged for the arms —10—: Each of the arms —10— is 105 pressed by means of a spring —16— to the surface of the cylinder —14— supporting the star-wheel —15— and provided with six indentations —17— Fig. 3. These indentations lie on the surface of the cylinder in different heights, so that according to the 110 position of the cylinder, one or the other of the arms —10— will be pressed with its

free end into that indentation, which lies with it on the same height, whereby the wheel —11— of the arm will be connected with the corresponding wheel —13—. The cylinder —14— is adapted to be adjusted by means of the lever —21— carrying the pawl 18, which is held in engagement with the star wheel 15 by means of the spring 20, on the lever 21, the said lever being operated by means of the press button 19. By these means the cylinder 14 can be brought into seven different positions, in one of which a plain part of the cylinder lies before the ends of the arms —10—, so that then all wheels —11— are out of connection and the time-beating mechanism is at rest. But if one of the wheels —11— is inserted, the wheel turns, by means of the corresponding wheel —12—, the wheel —22—, which gears with all the wheels —12— and the axle —23— of which, being elongated to the dial plate, supports under that plate the toothed wheel —24—. With this wheel gears the extension —25— of the hammer —26— turnable against the action of a spring, so that the hammer, according to the number of revolutions of the wheel —24— that is to say according to the inserted wheel —11—, will exert more or less strokes on the spring —27—.

In order to facilitate the adjustment of the different times, the axle of the cylinder —14—, elongated to the dial plate, is provided with the hand —28— (Fig. 2.) which, actuated by the button —19—, moves over the graduation —29— showing the figures corresponding to the different times.

The described watch may of course be varied in numerous ways according to its

practical employments, without modifying the essential feature of the invention.

What I claim and desire to secure by Letters Patent of the United States is:

1. Improved time beating mechanism comprising the combination of a watch driving mechanism, a plurality of pivoted arms each carrying a gear wheel, a plurality of wheels each having a different number of teeth mounted on a single shaft of the watch mechanism and each wheel being adapted to gear with a wheel on one of the pivoted arms, means for selecting and bringing one pair of wheels into gear so that a predetermined and variable speed is obtained and means for audibly beating the selected periodicity. 45 50 55

2. Improved time beating mechanism comprising the combination of a watch driving mechanism, a plurality of pivoted arms each carrying a gear wheel, a plurality of wheels each having a different number of teeth mounted on a single shaft of the watch mechanism and each wheel being adapted to gear with a wheel on one of the pivoted arms, means for selecting and bringing one pair of wheels into gear so that a predetermined and variable speed is obtained, a visual indicator showing the selected periodicity and means for audibly indicating such periodicity. 60 65 70

In testimony, that I claim the foregoing as my invention, I have signed my name in presence of two subscribing witnesses.

HUGO MELOCCO.

Witnesses:

E. H. KELEMEN,
HUGH KEMINY.
